DESIGN FOR AN EMBROIDERED TRIMMING

Hans Tobler and Otto Hallbauer,
Union City, N. J.

Application December 8, 1939, Serial No. 88,763

Term of patent 3½ years

To all whom it may concern:

Be it known that we, Hans Tobler and Otto Hallbauer, citizens of the United States of America, residing in Union City, county of Hudson, and State of New Jersey, have invented a new, original, and ornamental Design for an Embroidered Trimming, of which the following is a specification, reference being had to the accompanying drawing, forming part thereof, wherein the figure is a plan view of a piece of embroidered trimming showing our new design.

We claim:

The ornamental design for an embroidered trimming, substantially as shown.

HANS TOBLER.
OTTO HALLBAUER.
